ARKELL & SMITHS, OF CANAJOHARIE, NEW YORK, A CORPORATION OF NEW YORK.

MULTI-PLY BAG.

Application filed July 28, 1925. Serial No. 46,540.

Our invention relates to multi-ply bags, more particularly to multi-ply paper bags for cement and other weighty substances, and has for its object to provide a novel 5 paper bag made of two or more thicknesses in which the closure at the top or bottom is formed by securing overlapping flaps by glue or other adhesive, each ply being secured substantially independently of the 10 other so as to form a firmly secured yet supple flat closure. Another object of our invention is to provide a flat closure multi-ply bag, the closure of which is secured by glue applied to one side only of the several plies 15 of the flap in an ordinary bag closure forming machine.

The following is a description of our invention as embodied in our improved bag and the method of producing the same, reference being had to the accompanying drawings, in which,

Fig. 1 shows in perspective the bag having bottom and top closures embodying our invention;

Fig. 2 shows the method of forming multi-ply tube sections for our improved bag;

Fig. 3 shows one of these sections unfolded;

Fig. 4 shows one of these sections with the 30 flaps laid back to show more clearly the relations of the seams in the outer and inner layers of two-ply tubing;

Fig. 5 is an enlarged detail of one of the tube sections, parts being broken away;

Fig. 6 is a section on the line 6—6, Fig. 5;

Fig. 7 is a tube section of Fig. 5, after the first bottoming folds have been made;

Fig. 8 is a section on the line 8—8, Fig. 7;

Fig. 9 shows the completed bottom of the 40 bag with parts turned back and parts broken away;

Fig. 10 is a section on the line 10—10, Fig. 9;

Fig. 11 shows the seal after the first sealing folds are made and the glue applied, a portion being broken away;

Fig. 12 shows a tube section for a three-ply bag, parts being broken away, and parts folded back; and

Fig. 13 shows a tube section of Fig. 12, after the first bottoming folds have been made and adhesive applied.

Referring more particularly to the drawings, Fig. 1 shows the complete bag with the

folded bottom closure 2 and the folded 55 valve closure 4. In making this bag we first form a tube 6 which is cut up into sections 8. As each section 8 is cut off we fold about it the sheet 10, as shown at 12. In forming these tubes adhesive is applied to the outer 60 or overlapping edges, so that when the tube is folded the two edges of the respective plies are secured together. After the sheet 10 is formed into a tube about a section 8 it is severed at a point 14 midway between successive sections 8, which sections are spaced apart, as shown at 16, so that the outer tubular section extends beyond the inner tubular section at both ends, producing what is hereafter described as a shingle effect. In forming these sections the ordinary grip tab 18 is formed at one end on the outer ply of the section and a corresponding recess is formed on the opposing end of the outer ply of the preceding section.

Prior to the folding of the outer ply about the inner ply, short longitudinally extending lines of adhesive 20 are applied to the bottom and top surfaces of the inner tube, extending a few inches from each end so that 80 the inner ply is locally secured to the outer ply adjacent to its top and bottom ends, so as to enable the multi-ply tube to be bottomed and sealed in ordinary bottoming and sealing machines. These short lines of the 85 glue upon the top and bottom ends of the inner ply are shown in dots in the developed Fig. 3, and are also shown in the sectional view, Fig. 6, which also shows the adhesive strips 22 and 24 securing the edges of the 90 tubes.

The bottom end of the tube is then slit along the lines 26 and the resulting side flaps 28 and 30 pulled in one direction, while the side flaps 32 and 34 are pulled in the 95 opposite direction, as shown in Fig. 7. This is done by pulling on the outer flaps 28 and 32, the inner flaps 30 and 34 following on account of the adhesive 20 locally connecting them thereto. This causes the edges of the 100 bag 36 and 38 to fold inwardly to form end flaps as shown in Fig. 7, the side and end flaps to lie in substantially the same surface, which, in the bottoming machine, conforms to the surface of a cylinder. After the parts 105 have been thus opened up, adhesive 40 is applied to the exposed faces of the shingled side flaps 28 and 30 and the exposed faces

of the end flaps 36 and 38, this adhesive being in the shape of a letter **U**. After the adhesive has been applied, one portion of the bottom with the side flaps 32 and 34 is folded over along the line 42, and the other, with the side flaps 28 and 30, is folded over on top of it along the line 44, as shown in Fig. 10, producing the bottom of the bag, as shown in Figs. 1 and 9. It will be noted that when so folded the flap 30 is secured to the end of the flap 32 at one point, while the flap 28 is secured to said flap 32 a little further along. There being no extended glue between the opposing faces on the flaps 28 and 30, the flap 30 is secured to the flap 32 substantially independently of the flap 28 and the flap 28 is secured to the flap 32 substantially independently of the flap 30. This securing of these flaps of the several layers substantially independently results in a stronger seal than would be present if the flaps 28 and 30 were of equal length, and the flap 28 was not directly secured to the flap 32, and, furthermore, results in a more supple bottom than if the glue were interposed between the flaps 28 and 30. The side flaps 32 and 34 are also secured by adhesive to the end flaps 36 and 38. One end flap being folded along the line 44 has one outer portion glued to another portion of itself and to the outer surface of flap 32 (Fig. 10).

It will be noticed that in the central portion of the bottom of a two-ply bag (Figs. 9 and 10), the paper between the ends of the end flaps 36 and 38 is only three-ply and that in a section which includes either end flap 36 or 38, there are five layers of paper. If the two layers of paper of the multi-ply tube did not overlap at the tube end there would be four thicknesses of paper on the section between the end flaps 36 and 38 and six layers of paper on the section passing through either end flap 36 and 28, and extended intermediate adhesive would be required to secure the outer ply of the outer side flap.

The several plies of the overlying side flap have portions in direct contact with the outer ply of the other side flap and secured thereby by adhesive, and the end edges of the plies of said outer side flap are parallel to the end edges of the plies of said inner side flap.

In forming the valve 4, the construction is the same except that the flaps are shorter, as shown in Fig. 11, and one leg of the adhesive **U** is shortened, as shown at 46 in Fig. 11 so as not to fully seal one end flap. It will be seen, however, that the valve can still be formed in our improved multi-ply bag, and the advantages of the separate securing of the plies of the flaps retained.

When a bag having a greater number of thicknesses, such as a three-ply bag, is desired a similar procedure is followed, there

being three tubular sections closely fitting in one another, the flaps successively increasing in length from the inner flap out, as shown in Figs. 12 and 13, glue being locally applied to both sides of the inner tube 70 sections, along longitudinal lines for short distances, as shown at 48 and 50, Fig. 12. The bottom is slit and opened as before and adhesive is then applied to all of one set of flaps 52, and across the outer side flaps 54 75 and 46, whereupon the bag bottom is folded first along the line 58 and then along the line 60 so as to complete the bottom, the three side flaps 52 of the bottom being in this case also substantially independently 80 secured to the outer ply of the side flap 62, so as to secure the advantage of independent gluing and the flexibility due to the omission of extended adhesive between the layers 85 of the flaps.

In forming the multi-ply tube an inner section tube acts as a former proving a folding edge for the surrounding outer tube, so that the tubes fit each other closely, with the result that any strain upon an inner tube 90 is transmitted to its next succeeding tube and all tubes act together to simultaneously resist such strain. In the bottom also any strain which is present will be simultaneously resisted by the plies of the flap to which the glue is applied, and much of it is transmitted by the end flaps 36 and 38 to the side flap 34 so that the inner ply 34 in the flap portions 32-34 relieves to some extent strain upon the outer ply 30. The extension of the flap 28 beyond the flap 30 produces a shingle effect similar to the shingles upon a roof, and the glue applied to the flaps 28 and 30 for that reason does not substantially work beneath the ply 30, although in the squeezing operation in manufacture it may work beneath the ply 30 to a slight extent, but not so as to interfere with the advantage of single-ply gluing above referred to. In view of this we have referred to the flaps 28 and 30 as shingled 100 flaps, meaning thereby partially overlapping flaps for producing the results above specified.

In carrying out the method of producing a two-ply valved bag in accordance with our invention, we first form a two-ply tube in which the ends of the inner ply are out of alignment with the ends of the outer ply so as to produce an internal shingled effect, the inner ply being secured to the outer ply on both sides by short lines of adhesive adjacent to the ends of the inner ply. We then slit the ends of the tube so as to form opposed side and end flaps and separate the side flaps, and after applying adhesive to one set of side flaps and to the end flaps, fold the other set of side flaps in and then fold the adhesive bearing side flap over on to them and thus produce the desired closed 115 120 125 130

bottom. The valve is produced in a similar manner except for the omission of the adhesive on a part of one end flap.

As will be evident to those skilled in the art, our invention permits of various modifications without departing from the spirit thereof or the scope of the appended claims.

What we claim is:

1. In a multi-ply bag, the combination of two tubes, one fitting within the other and in shingled relation at adjacent ends thereof, said shingled ends having inwardly extending multi-ply end flaps and inwardly extending shingled multi-ply side flaps overlapping said end flaps, one of said multi-ply side flaps overlying the other multi-ply side flap, and adhesive independently securing the shingled portions of the several layers of the multi-ply side flap directly to the external layer of the other multi-ply side flap.

2. In a multi-ply bag, the combination of two tubes, one fitting within the other and in shingled relation at adjacent ends thereof, said shingled ends having inwardly extending multi-ply end flaps and inwardly extending shingled multi-ply side flaps overlapping said end flaps, one of said multi-ply side flaps overlying the other multi-ply side flap, and adhesive independently securing the shingled portions of the several layers of one multi-ply side flap directly to the external layer of the other multi-ply side flap, and adhesive securing an inner and outer shingled layer of the under multi-ply side flap directly to the outer layers of the end flaps.

3. In a multi-ply bag, the combination of two tubes, one fitting within the other and in shingled relation at adjacent ends thereof, said shingled ends having inwardly extending multi-ply end flaps and inwardly extending shingled multi-ply side flaps overlapping said end flaps, one of said multi-ply side flaps overlying the other multi-ply side flap, adhesive independently securing the shingled portions of the several layers of one multi-ply side flap directly to the external layer of the other multi-ply side flap, adhesive securing an inner and outer shingled layer of the under multi-ply side flap to the outer layers of the end flaps, and adhesive securing the inner layer of the outer multi-ply side flap to the outer layers of the end flaps.

4. In a multi-ply bag, the combination of two tubes, one fitting within the other and in shingled relation at adjacent ends thereof, said shingled ends having inwardly extending multi-ply end flaps and inwardly extending shingled multi-ply side flaps overlapping said end flaps, one of said multi-ply side flaps overlying the other multi-ply side flap, and adhesive independently securing the shingled portions of the layers of one

multi-ply side flap directly to the external layer of the other multi-ply side flap, successive layers of the multi-ply side flaps being locally secured to each other directly by adhesive.

5. In the method of making a multi-ply bag, the improvement which consists in forming a tubular section and forming about said tubular section a second tubular section, and spacing the end of said first section within and away from the corresponding end of the outer tube section so as to produce a shingled relation, securing opposing surfaces of said sections together locally adjacent to the spaced away end of the inner section, slitting the spaced ends of said tube sections to form two shingled side flaps and two end flaps, folding said end flaps inwardly and then folding said side flaps inwardly and securing the several plies of the outer shingled side flap directly to the outer ply of the inner side flap by adhesive.

6. In a multi-ply bag, the combination of two tubes, one fitting within the other and in shingled relation at adjacent ends thereof, said shingled ends having inwardly extending multi-ply end flaps and inwardly extending multi-ply side flaps having shingled portions overlapping said end flaps, one of said multi-ply side flaps overlying the other multi-ply side flap, and adhesive independently securing shingled portions of the several layers of one multi-ply side flap to the external layer of the other multi-ply side flap, and adhesive separately securing the shingled portions of the inner and outer layers of the under multi-ply side flap directly to the outer layers of the end flaps.

7. In a multi-ply bag having two tubular sections, one being within the other and shingled at adjacent ends thereof, inwardly extending multi-ply end flaps, inwardly extending multi-ply side flaps overlapping said end flaps, one end of said overlying multi-ply side flap overlapping the other multi-ply side flap, the several plies of the overlying side flap each having shingled portions contacting directly with the outer ply of the other side flap and adhesive securing said contacting portions of said several plies directly to said outer ply, the end edges of the plies of said outer side flap being parallel to the end edges of the plies of said inner side flap.

8. In a multi-ply bag having two tubular sections, one being within the other and shingled at adjacent ends thereof, inwardly extending multi-ply end flaps, inwardly extending multi-ply side flaps overlapping said end flaps, one end of said overlying multi-ply side flap overlapping the other multi-ply side flap, the several plies of the overlying side flap having shingled portions contacting directly with the outer ply of the other side flap and adhesive securing said

contacting portions of said several plies to said outer ply, the end edges of the plies of said outer side flap being parallel to the end edges of the plies of said inner side flap, and the several plies of the underlying side flap each having portions making direct contact with the outer plies of said end flaps

and adhesive securing the same to the other plies of said end flaps.

In testimony whereof, we have signed our names to this specification this 25th day of July, 1925.

JOHN N. TOOKER.
JOHN F. HARLEY.
